WOODWORKING MACHINE ATTACHMENT
TO A JIG SAW

Frederick J. Tollafeld, Detroit, Mich.

Application June 18, 1947, Serial No. 755,283

6 Claims. (Cl. 144—1)

1

This invention relates to woodworking machines, and in particular to convertible woodworking machines, having interchangeable attachments for performing different woodworking operations.

One object of this invention is to provide a convertible woodworking machine consisting of a jigsaw having a frame with an upright upon which various interchangeable attachments may be clamped for performing different woodworking operations, for example, a circular saw, a shaper or planer, a lathe, a drill press, a band saw, and a rotary spindle which is adapted to interchangeably receive a grinding wheel, a buffering wheel or a sanding disc.

Another object is to provide a convertible woodworking machine, as set forth in the preceding object, wherein the various attachments have slotted legs by which they are secured to the upright portion of the jigsaw frame, the shafts of the various attachments having pulleys which are in line with a pulley upon the jigsaw machine so as to be driven from the last-mentioned pulley.

Another object is to provide a convertible woodworking machine, as set forth in the preceding objects, wherein the upright portion of the jigsaw is provided with a machined portion and the various attachments are provided with mating machined portions, the aforesaid machined portions being clamped into engagement with one another so that all of the attachments fit onto the same machined portion of the jigsaw frame.

Another object is to provide a convertible woodworking machine, as set forth in the preceding objects, wherein the attachments are provided with rotary shafts supported in spaced bearings which are interconnected by an attachment frame, the attachment frame having an upright portion which is releasably attachable to the upright portion of the jigsaw frame.

Another object is to provide a convertible woodworking machine, as set forth in the preceding objects, wherein the jigsaw frame is provided with a pair of spaced upright portions and the various attachments each provided with a pair of spaced legs releasably attachable to these upright portions.

Another object is to provide a convertible woodworking machine, as set forth in the object immediately preceding, wherein the spaced legs are apertured to receive fasteners by which the attachment legs are clamped to the upright portions of the jigsaw frame.

Another object is to provide a convertible woodworking machine, as set forth in the preceding

2

objects, wherein the attachment frame is movable vertically relatively to the jigsaw frame so as to provide for tightening or loosening the belt by which a pulley on the attachment drive shaft is driven by a pulley on the jigsaw machine.

Another object is to provide a convertible woodworking machine, as set forth in the object immediately preceding, wherein the attachment frame is movable vertically by a manually operated cam mechanism for tightening or loosening the driving belt.

Another object is to provide a convertible woodworking machine, as set forth in the preceding objects, wherein the various attachments are attachable and detachable at will, thereby enabling the owner of the machine to perform a wide variety of operations which would otherwise require the purchasing of separate machines and the increased space in which to mount such machines, so that the owner thereby avoids both the expense of the separate machines themselves, as well as the cost of the space for them.

In the drawings:

Figure 1 is a side elevation of a convertible woodworking machine, primarily a jigsaw, according to a preferred form of the invention, partly broken away to show the clutching arrangement and also the clamping device for the various attachments, the attachment shown being a planer;

Figure 2 is a right-hand end elevation of the jigsaw and planer attachment shown in Figure 1;

Figure 3 (Sheet 1) is a horizontal section along the line 3—3 in Figure 1, showing details of the mounting legs for the attachment machines and the manner in which they are clamped to the upright portion of the jigsaw frame;

Figure 4 (Sheet 3) is a front elevation of a bandsaw attachment, interchangeable with the planer attachment on the jigsaw shown in Figure 1;

Figure 5 is a right-hand side elevation of the band saw attachment shown in Figure 4;

Figure 6 (Sheet 2) is a front elevation of a circular saw attachment interchangeable with the planer attachment of the jigsaw shown in Figure 1;

Figure 7 is a right-hand side elevation of the circular saw attachment shown in Figure 6;

Figure 8 is a horizontal section along the line 8—8 in Figure 7, showing details of the attachment frame;

Figure 9 is a front elevation of a drill press attachment interchangeable with the planer attachment of the jigsaw shown in Figure 1;

Figure 10 is a horizontal section along the line

10—10 in Figure 9, showing details of the attachment frame;

Figure 11 is a front elevation of a disc sander attachment, the spindle of which optionally receives grinding or buffing wheels, interchangeable with the planer attachment on the jigsaw shown in Figure 1;

Figure 12 is a front elevation of a wood-turning lathe attachment interchangeable with the planer attachment on the jigsaw shown in Figure 1;

Figure 13 is an enlarged fragmentary side elevation of the upright portion of a jigsaw employing a modified attachment frame from those shown in Figures 1 to 12 inclusive;

Figure 14 is a fragmentary vertical section along the line 14—14 in Figure 13; and

Figure 15 is a fragmentary horizontal section along the line 15—15 in Figure 14.

Referring to the drawings in detail, Figures 1 and 2 show a convertible woodworking machine, generally designated 10, as consisting primarily of a jigsaw, generally designated 11, and an attachment machine, generally designated 12, attachable to an upright portion of the jigsaw frame as described hereinafter in more detail. The numeral 12 for the attachment machine shown in Figure 1 is used herein as a general designation for all of these attachment machines, considered generically. The particular attachment machine shown in Figure 1 is also generally designated 13, the latter designation referring to it as a planer attachment.

Interchangeable with the planer attachment 13 shown in Figure 1 are other attachment machines 12, such as the band saw attachment machine, generally designated 14, shown in Figures 4 and 5; the circular saw attachment machine, generally designated 15, shown in Figures 6, 7 and 8; the drill press attachment machine, shown in Figures 9 and 10; the rotary disc attachment machine, generally designated 17 shown in Figure 11 and optionally receiving a sanding disc, a grinding wheel or a buffing wheel; and a wood-turning lathe attachment machine, generally designated 18, shown in Figure 12. All of these attachment machines 12 may be interchangeably substituted for one another in the position shown in Figure 1, and driven from the same pulley on the jigsaw 11.

The jigsaw 11 consists of a base or subframe 19 (Figures 1 and 2) having attachment feet 20 for mounting upon a bench or other suitable support. Bolted, as at 21, to the subframe, is an L-shaped hollow frame member or bracket 22 including a vertical frame portion 23 from which a horizontal frame portion 24 extends approximately parallel to the base or subframe 19 in overhanging relationship therewith. Also bolted as at 25 to the subframe 19 is an auxiliary frame upright 26 substantially parallel to the upright frame portion 23. It is to these vertical frame portions or members 23 and 26 that the various attachment machines 12 are releasably clamped, as described below.

The working parts of the jigsaw 11 are mainly conventional, aside from the manner of supporting and driving the attachment machines. The portions of the machine 10 which primarily belong to the jigsaw 11 are therefore shown diagrammatically. The subframe 19 is hollow and has a plurality of downwardly projecting bosses or lugs 27 to 33 inclusive, the boss or lug 33 forming a portion of one of the end walls 34 and 35 of the subframe 19. The end walls 34 and 35 are of roughly triangular shape (Figure 2) with the op-

posite side walls 36 and 37 inclined upward to meet a narrow top wall 38.

Journalled in the bosses 28 and 29 is a shaft 39 (Figure 1), the left-hand end of which carries a disc 40 with an eccentric pin 41 mounted in an eccentric bore 42 near the periphery thereof. The pin 41 pivotally engages a bore 43 in one end of a link or pitman 44, the other end of which is bored as at 45 to receive a pin 46 connected to a crosshead or block 47 having a vertical bore 48. Mounted in the vertical bore 48 and secured therein, as at 49, is a vertically reciprocable shaft 50. The latter is reciprocably mounted in a vertical bore 51 in the boss or lug 27, and the upper end carries a lower chuck 52 adapted to hold the lower end of a jigsaw blade 53. The latter passes upward through a hole 54 in a worktable 55 and its upper end is held in an upper chuck 56. The upper chuck 56 is mounted upon the lower end of a vertically reciprocable shaft or plunger 57 which is movable up and down in a bore 58 in the outer end of the horizontal portion 24 of the frame member or bracket 22. At the top of the frame portion 24 a recess 59 is provided for a cup-shaped cap 60. The latter serves as an enclosure for the upper end of the shaft 57 and a coil spring 61 which surrounds it. One end of the coil spring 61 is seated against the bottom of the recess 59 and the other end engages a head 62 on the upper end of the shaft 57. The coil spring 61 constantly urges the shaft 57 upward and maintains the saw blade 53 in a taut condition while it is reciprocated vertically by the mechanism described above.

The outer end of the horizontal portion 24 of the frame member 22 is provided with a vertical bore 63 in which is mounted a presser foot shaft 64, preferably of square cross-section and having a forked presser foot 65 secured to the lower end thereof and extending on opposite sides of the saw blade 53. The presser foot shaft 64 is adjustable vertically in order to adapt it to varying thicknesses of workpiece, and is clamped in a vertical position of adjustment by the adjusting screw 66. The worktable 55 with which it cooperates is provided with a pair of parallel downwardly-extending arms 67 which are pivotally and adjustably secured to the arms of a U-shaped frame 68 by bolts 69. The U-shaped frame 68 is mounted on the subframe 19 above the previously described mechanism for reciprocating the saw blade 53.

Mounted near the inner end of the shaft 39 (Figure 1), is a movable clutch collar 70 which is splined or keyed as at 71 to the shaft 39 so as to establish a driving connection therewith. The clutch collar 70 is provided with clutch notches 72 which are engageable with projections 73 (one only of the notches 72 and projections 73 being shown) on a clutch collar 74. The clutch collar 74 has a bore 75 therein, the forward end of which receives the adjacent end of the shaft 39 and the rearward end of which receives the forward end of a drive shaft 76 and is pinned thereto as at 77. The drive shaft 76 is journaled in the downwardly-extending bosses 30 and 31, and carries a pulley 78 which is secured thereto in driving relationship. The pulley 78 is driven by a belt 79 from a motor or other suitable source of power.

The opposite end of the shaft 76 is connected to a shaft 80 by means of fixed and movable clutch collars similar to the clutch collars 70 and 74 which are described and, hence, having simi-

larly designated parts (Figure 1). Each of the collars 70 has an annular groove 81 therein. The left-hand clutch unit, generally designated 82, (Figure 1), is actuated by pins 83 in a clutch-shifting yoke 84. The right-hand clutch unit, generally designated 85, is similarly actuated by pins 86 in a clutch-shifting yoke 87. The clutch-shifting yokes 84 and 87 are similar in construction and are similarly pivoted, as at 88 (Figure 2), to bosses 89 (one only being shown), rising from the subframe side wall 36.

The shaft 89 is journaled in the bosses 32 and 33 extending downward within the subframe 19 (Figure 1), and on its outer end carries a pulley 90 by which the various attachment machines are driven. The uprights 23 and 26 are provided with machined flat surfaces 91 and 92 having oppositely-facing vertical grooves 93 and 94 respectively (Figure 3). The upright 23 is provided with an internal boss 95 (Figure 1) which has a threaded bore 96 adapted to receive a cap screw 97. Similarly, the upright 26 is provided with a threaded bore 98 adapted to receive a cap screw 99 facing in the opposite direction. The uprights 23 and 26 are provided with aligned transverse bores 100 and 101 in which are journaled the opposite ends of a cam shaft 102 having cams 103 and 104 pinned or otherwise secured thereto near the opposite ends thereof. The upright 26 is cut away as at 105 to receive the cam 104. An operating arm or handle 106 is pinned or otherwise secured to the cam shaft 102.

Planer attachment

The planer attachment 13, shown in Figure 1, has spaced supporting legs 107 and 108 (Figures 1, 2 and 3) which are slotted as at 109 with inverted U-shaped slots, to receive the cap screws 97 and 99. The legs 107 and 108 are provided with projecting ribs 110 and 111 facing in opposite directions and mating with the grooves 93 and 94 (Figures 1 and 3). The lower ends of the legs 107 and 108 rest upon the peripheries of the cams 103 and 104. Consequently, when the cap screws 97 and 99 are loosened, the legs 107 and 108 and the machine attached thereto may be moved up and down by swinging the arm or handle 106, thereby tightening or loosening the belt 112 by which the attachments 12 are driven from the pulley 90.

The slotted legs 107 and 108 are interconnected by a tie member 113 (Figure 3) which has a laterally-projecting portion 114 containing an end slot 115 forming a pair of spaced arms 116 having aligned bores 117 in which pivot pins 118 are journaled (Figure 2). The pivot pins 118 are either integral with or mounted on a hub 119 having a vertical bore 120 therein containing a threaded rod 121. Lock nuts 122 and 123 above and below the hub 119 serve to lock the rod 121 in position after it has been moved upward or downward within the bore 120. The upper end of the rod 121 terminates in a head 124 pivoted on a pivot pin 125 supported by spaced ears 126 extending downward from a work table 127. The work table 127, remote from the ears 126, is provided with additional spaced ears 128 which support pivot bolts 129 (Figure 2) by which the work table 127 is adjustably and pivotally mounted on arms 130 extending upward and rearward from the legs 107 and 108.

The work table 127 is provided with an elongated aperture 131 (Figure 2) through which project the cutting blades 132 mounted on a planer 75

hub 133 which is slotted as at 134 for that purpose. The planer hub 133 is keyed or otherwise drivingly secured to a shaft 135 journaled in aligned bearing bosses 136 projecting outward in opposite directions from the legs 107 and 108. The shaft 135 carries a pulley 137 over which is trained the belt 112 (Figure 1). The hub of the pulley 137 is secured as by the pin 138 to the shaft 135.

Bandsaw attachment

The bandsaw attachment 14 (Figures 4 and 5) consists of a pair of spaced legs 140 similar to the spaced legs 107 and 108 of the planer attachment 13 and similarly provided with inverted U-shaped slots 141 adapted to slip over the shanks of the cap screws 97 and 99 and having similar ribs 142 engageable with the slots 93 and 94 (Figures 5 and 3). The forward and rearward sides of the legs 140 are interconnected by plates or bars 143 and 144 bolted thereto. The bar 144 is extended beyond the end of the bar 143 and has connected thereto a vertical approximately arcuate bracket 145 extending above and below the bar 144 and having bosses 146 and 147 at its upper and lower ends respectively. Mounted in the bosses 146 and 147 are stub shafts 148 and 149 (Figure 4) on which are mounted the bandsaw pulleys or discs 150 and 151. Trained over the bandsaw discs 150 and 151 is an endless bandsaw 152.

The bandsaw pulleys or discs 150 and 151 are rotated by a pulley 153 (Figure 4) secured to the disc 151 and driven by a belt 154 from a pulley 155 secured to the end of a shaft 156 journaled in the sleeves 157 and 158 mounted in the upper end of the legs 140. The shaft 156 is driven by a pulley 159 mounted thereon and in turn driven by the belt 112 (Figure 1). The pulley 153 therefore corresponds to the pulley 137 of the planer attachment 13. The bandsaw attachment 14 is provided with a worktable 160 which has downwardly-extending ears 161 journaled on the sleeves 157 and 158. The worktable 160 is provided with an aperture 162 through which passes the bandsaw 152. In order to tilt the worktable 160 at the desired angle, one of the ears 161 is provided with an integral boss 163 (Figure 5) which is provided with a threaded bore 164 containing a thumb screw 165. By loosening the thumb screw 165, the worktable 160 may be tilted around the sleeves 157 and 158, after which the thumb screws 165 may be tightened to lock the worktable 160 in its adjusted position.

Circular saw attachment

The circular saw attachment 15 (Figures 6, 7 and 8) is provided with a pair of spaced legs 170 with inverted U-shaped slots 171 similar to the slots 141 and 109 of the bandsaw and planer attachments 14 and 13 respectively, and similarly provided with outwardly-facing ribs 172. As before, the slots 171 and ribs 172 serve to engage the cap screws 97 and 99 and vertical grooves 93 and 94 in the uprights 23 and 26 respectively (Figures 1 and 3). The legs 170 are interconnected by webs 173 (Figure 8) to render the structure rigid. Journaled in the oppositely-facing bosses 174 at the upper end of the legs 170 is a rotary shaft 175 carrying a pulley 176 and a circular saw 177 secured thereto by a washer or collar 178 and nut 179, the latter being threaded upon the end of the shaft 175. The pulley 176 is so located as to be directly above

the pulley 90 (Figure 1) and driven by the belt 112 when it is in position upon the machine 10.

The circular saw attachment 15 is provided with a tiltable work table 179 having downwardly-extending ears 180 at its opposite sides, the ears 180 being pivotally mounted, as by the pivot pins 181, upon the angle arms 182 having their horizontal portions secured, as at 183, to the upper ends of shafts 184 passing through vertical bores 185 in bosses 186 extending outward in opposite directions on opposite sides of one of the legs 170. Set screws 187 threaded into the bosses 186 and engaging the shafts 184 serve to lock the latter in their vertical positions of adjustment. By varying the adjustment of the shafts 184 up or down, the depth of cut taken by the circular saw 177 is correspondingly adjusted. The circular saw 177, as usual, projects through a slot 188 in the top of the worktable 179 which, as previously stated, is tiltably mounted upon the pins 181 serving as trunnions.

In order to lock the worktable 179 in its tilted position, the former is provided with a downwardly-extending ear 189 into which is threaded a pivot bolt 190 (Figures 6 and 7). Pivotally mounted upon the pivot bolt 190 is a link 191 having an elongated slot 192 therein. The slot 192 receives a stud or screw 193 which is threaded into a bore 194 in the outer end of an arm 195, the opposite end of the arm 195 being co-extensive with one of the angle arms 182. Thus, by loosening the screw 193 by means of the handle 196, the link 191 can be unclamped from the arm 195, so that the left-hand end of the table 179 (Figure 6) may be swung upward or downward around the trunnion pins 181.

Drill press attachment

The drill press attachment 16 (Figures 9 and 10), the disc sander or grinding wheel attachment 17 (Figure 11), and the lathe attachment 18 (Figure 12) are supported on similar pairs of spaced legs 200 which are therefore similarly designated by reference numerals. Like the legs 107 and 108 of the planer attachment 13 (Figures 1, 2 and 3), the legs 140 of the bandsaw attachment 14 (Figures 4 and 5) and the legs 170 of the circular saw attachment 15 (Figures 6, 7 and 8), the legs 200 are longitudinally slotted, as at 201 (Figure 10) to receive the shanks of the cap screws 97 and 99, and are also provided with longitudinal ribs 202 similar to the ribs 110 and 111 (Figure 3), 142 (Figure 5) and 172 (Figure 7) and for the same purpose. The legs 200 are also similarly interconnected by webs 203 (Figure 10) as in the other attachments previously mentioned. The legs 200 of the attachments 16, 17 and 18 near their upper ends are also provided with oppositely-facing bosses 204 with aligned bores 205 therein. Journalized in the aligned bores 205 is a shaft 206 near one end of which is secured the hub of a pulley 207 adapted to be driven from the pulley 90 (Figure 1) by the belt 112.

In the drill press attachment 16 (Figure 9) a work table 208 is mounted upon and integral with the bosses 204 and serves additionally to interconnect them as well as to provide a support for the workpieces to be drilled. Bolted to the work table 208 is a vertical column 209 having a pair of bearing arms 210 and 211 in which is mounted a quill 212. The quill 212 is keyed or splined to the arms 210 to prevent its rotation, and within the arm 211 is provided with rack teeth (not shown) engaged by a pinion mounted on a transverse shaft 213 which is journaled in the arm 211.

Mounted on one end of the shaft 213 is a hand lever 214. By swinging the hand lever vertically, the quill 212 is moved up and down.

Journaled in the quill 212 is a rotary shaft 215 upon which is mounted a pulley 216 and a driving connection established therebetween by a key or spline, as is well known in conventional drill press construction. Mounted on the lower end of the shaft 215 is the usual drill chuck 217 in which standard drills may be mounted. Extending rearwardly and upwardly from the column 209 is an arm 218 in the end of which a shaft 219 is mounted and which carries a pair of loose pulleys or idler pulleys 220 (one only being shown). An endless belt 221 is trained over the pulleys 216, 219 and 220 and also around a pulley 222, the hub of which is mounted on the shaft 206 so as to be driven therefrom. The details of the drill press above the work table 208 are conventional.

Disc sander and grinder attachment

The disc sander and grinder attachment 17 (Figure 11) as regards its legs 200, web 203, shaft 206 and pulley 207 has already been described in connection with Figure 9. The shaft 206 in the attachment 17, however, is provided with an extended portion 223 upon which is mounted the hub of a sanding disc 224 to which a layer of sheet sanding material 225 is secured, as by a suitable adhesive. The hub of the disc 224 is provided with a bore 226 into which the shaft extension 223 projects, the hub being pinned, keyed or otherwise drivingly secured to the shaft portion 223. A pair of arms 227 is secured, as at 228, to one of the legs 200 on opposite sides thereof (one arm only being shown) and these are bent downward past the periphery of the sanding disc 224. Secured to the end portions of the arms 227 is a work rest 229. Since the shaft 206 is adapted to receive any rotatable object, it may obviously receive a grinding wheel or buffing wheel in place of the sanding disc 224, and the invention so comprehends. A collar 230 secured to the left-hand end of the shaft 206 prevents end play of the latter, suitable thrust bearings (not shown) being of course provided in actual practice.

Lathe attachment

The lathe attachment 18, as regards its legs 200, and shaft 206 has already been discussed in connection with Figure 9 and this requires no repetition. Like the drill press attachment 16, the bosses 204 at their upper ends carry a table 231 which is preferably integral with the bosses 204 and serves as an additional strengthening member as well as a support for a lathe bed 232 bolted thereto as at 233. The lathe bed 232 is provided with the usual slotted or grooved ways (not shown) on which are slidably mounted a tool rest slide 234 and a tail stock 235. Mounted on the tool rest slide 234 is a conventional T-shaped tool rest 236, the shank of which is adjustable vertically and is clamped in position by the set screw 237. The tail stock 235 is provided with the usual dead center or tail stock spindle 238 which is movable to and fro by means of the hand wheel 237. Both the tool rest slide 234 and the tailstock 235 may be clamped in position by the usual hand wheels and clamping screws (not shown) extending downward through the lathe bed 232, as is conventional in wood-turning lathe practice.

Mounted on the left-hand end of the lathe bed 232 remote from the tail stock 235 is a head

stock 239 in which is journaled a shaft or live spindle 240, the opposite end of which is journaled in a bearing bracket 241 extending upward from the lathe bed 232. The inner end of the shaft 240 carries the usual face plate 242 the center of which is bored to receive the live center 243, preferably with a tapered junction. Mounted on the shaft 240 between the head stock 239 and the bearing bracket 241 is the upper cone pulley 244 which is aligned vertically with a lower cone pulley 245 mounted on the left-hand end of the shaft 206. The cone pulleys 244 and 245 are drivingly interconnected by a belt 246 which may be shifted from one step to the other thereof to change speeds. A collar 247 is secured to the shaft 206 to prevent end motion, as in the disc sander attachment 17 previously described.

Modified attachment machine

The modified jigsaw generally designated 250, shown in Figures 13, 14 and 15, is generally similar to the jigsaw 11 and differs only in details. The sub-base or sub-frame 251 is provided, as before, with a drive shaft 252 journaled therein and having a clutch unit 253 similar to the clutch units 82 and 85 (Figure 1) and similarly provided with a fixed collar 254 which loosely receives the end of the shaft 252 and a movable collar 255 keyed as at 256 to the shaft 252 and slidable therewith. The collars 254 and 255 have interengaging recesses and projections 257 and 258 respectively. A shifting yoke 259 mounted on a shaft 260 which also carries a hand lever 261, is provided as before with pins 262 engaging an annular groove 263 in the clutch collar 255. The shaft 260 is journaled in the sub-frame 251 and shifting of the handle 261 drivingly connects or disconnects the shaft 252 to a shaft 264 on which the clutch collar 254 is fixedly mounted. The shaft 264 is journaled at one end in a bearing boss 265 and at its other end in a bearing bracket 266 bolted as at 267 to the extension 268 of the subframe 251. Mounted on the shaft 264 between the bearing boss 265 and the bearing bracket 266 is a double pulley 269 having twin grooves 270 and 271, either of which is adapted to receive a belt 272.

The upright 273 (Figure 13) which forms a portion of the upper frame 274 of the jigsaw 250 is provided, as in the principal form of the invention shown in Figure 1, with internal upper and lower bosses 275 and 276 respectively which have threaded bores 278 and 279 adapted to receive a cap screw 280 and a stud screw 281. The stud screw 281 serves as a pivot shaft for the hub of a cam 282 having a handle 283 attached thereto. The upright 273 is provided with a vertical groove 284 (Figure 15) similar to the vertical groove 93 (Figure 3) and serving to receive a cooperating rib 285 on the vertical portion 286 of a frame 287. The rib and groove 285 and 284 serve as guideways for the vertical adjustment of the frame 287 and the cap screw 280 serves to clamp the latter in place when the adjustment has been made. This adjustment is made by swinging the handle 283 to rotate the cam 282 (Figure 14) against the lower end of the frame upright portion 286.

The upright portion 286 of the frame 287 is provided with an elongated vertical slot 288 which serves to receive the shank of the cap screw 280 and which also receives a guide pin or stud 289 secured in the bore 290 in the upright 273. The pin 289 is of the same diameter as the shank of the cap screw 280, and serves to assist the rib 75

285 and groove 284 in preventing sidewise motion of the frame 287.

Extending outward from the lower end of the upright portion 286 of the frame 287 is an arm 291 which curves outward and upward parallel to the upright portion 286. These are provided respectively with bearing bosses 292 and 293 (Figure 13) in which are journaled a shaft 294 carrying the hub of a pulley 295a. The latter is aligned with one of the grooves 271 of the double pulley 269 and is driven therefrom by the belt 272. Mounted on the right-hand end of the shaft 294 between collars 295 and 296 is a circular saw 297, the latter being held in position by a nut 298 threaded upon the threaded portion 299 of the shaft 294.

The arm 291 is also provided with bosses 300 on its opposite sides (one only being shown in Figure 13) which are bored as at 301 to receive vertical rods or shafts 302. The shafts 302 are adjustable vertically in the bores 301 and are secured in their adjusted positions by set screws 303. Pinned or otherwise secured to the upper ends of the shaft 302 are two similarly directed offset arms or brackets 304 to which a work table 305 is pivotally secured, as by the pivot bolts 306 passing through the ears 307 depending from the work table 305. The pivotal construction just described is similar to that shown in Figures 7 and 8. The work table 305 is provided with the usual slot 308 for the passage of the upper portion of the circular saw 297.

Operation

In the operation of the invention, the jigsaw 11 is operated in the usual manner by placing a board or other workpiece upon the work table 55. The shifting yoke 84 is then shifted to move the clutch member 74 into engagement with the clutch member 74 and so throw in the clutch 82 (Figure 1), thereby establishing a driving connection between the shaft 39 and the pulley 78 on the shaft 76. The motor driving the belt 79 will then cause the rotation of the shaft 39 and consequent reciprocation of the plunger 50 and saw blade 53, sawing a slot in the workpiece as the operator moves the latter around over the work table 65.

Should the operator desire to plane the workpiece, he shifts it from the worktable 55 to the worktable 127. He then adjusts the rod 121 upward or downward to regulate the depth of cut of the cutter blade 132, if he has not already done so. He then shifts the shift yoke 87 to throw in the clutch 85, after having shifted the shift yoke 83 to throw out the clutch 82 and halt operation of the jigsaw 11. The throwing in of the clutch 85 causes rotation of the shaft 80 and pulley 90 and consequently rotates the pulley 137 and planer hub 133. The operator then moves the workpiece across the table 127 and over the aperture 131 containing the rapidly rotating blades 132, thereby taking a cut off the bottom of the workpiece, and planing its lower surface.

Should the operator desire to use the circular saw attachment 15, he loosens the cap screws 97 and 99 (Figure 1) unclamping the legs 107 and 108 from the uprights 23 and 26 of the jigsaw frame. With the legs 107 and 108 thus released, he swings the handle 106 to rotate the shaft 102 and the cams 103 and 104 to drop the legs 107 and 108 to their lowest positions, enabling the belt 112 to be removed from the pulley 137. The planer attachment 13 may then be lifted off the cap screws 107 and 108, withdrawing the ribs 119 and 111 from their respective grooves 93 and 94.

The circular saw attachment 177 is then installed by reversing the foregoing procedure, lowering it upon the cap screws 97 and 99 until they enter the slots 171 and the ribs 172 enter the grooves 93 and 94. When the ends of the legs 170 come to rest upon the cams 103 and these are rotated to their lowest positions by swinging the handle 106, the belt 112 is then trained over the pulley 176. The cam lever 106 is then swung downward to rotate the cams 103 and 104 and lift the circular saw attachment bodily, thereby tightening the belt 112. When the yoke 87 is then shifted to throw in the clutch 85, a driving connection is established between the circular saw shaft 175 and the shaft 76 driven by the pulley 78 and belt 79 from the driving motor, rotating the circular saw 177.

After the cap screws 97 and 99 have been tightened to clamp the legs 170 in their adjusted position, the operator places the workpiece upon the worktable 179 and moves it past the saw 177, cutting the desired portion off the workpiece. If an angular saw cut is desired, such as for a mitre joint in corner work, the work table 179 is tilted around its trunnion pins 181 by loosening the clamping screw 193, until the work table 179 is at the proper angle, say 45 degrees relatively to the plane of the circular saw 177. The work table 179 is then clamped in its adjusted position by swinging the handle 196 to tighten the clamping screw 173 against the link 181. The cut is then taken as before, with or without the use of a saw guide.

In a like manner, the circular saw attachment 15 may be removed and either the drill press attachment 16, disc sanding attachment 17, lathe attachment 18 or band saw attachment 14 substituted. These attachments 14, 16, 17 and 18 are operated in a similar manner to conventional bandsaws, drill presses, disc sanders and wood turning lathes respectively. The operation, as concerned with the adjustment of these attachments, has already been described in connection with their construction.

The operation of the modification shown in Figures 13, 14 and 15 is similar to that of the principal form of the invention shown in Figures 1 to 12 inclusive. This modification is of simpler construction for light duty work, whereas the construction shown in Figures 1 to 12 inclusive is most suitable for heavy duty work. The frame 287 (Figure 13) is adjusted up or down by loosening the cap screw 280 and swinging and handle 283 and cam 282, thereby tightening the belt 212 and establishing a driving connection between the pulleys 269 and 295. The worktable 305 is adjusted to the proper angle, if not already so adjusted, in a similar manner to that described in connection with Figures 6, 7 and 8. The workpiece is then sawed by shifting the clutch lever 261 to establish a driving connection between the shaft 252 and the shaft 264, rotating the circular saw 297. The cap screw 280 is, of course, tightened during this operation so as to secure the frame 287 rigidly to the upright 273. The remainder of the attachments used with the modification shown in Figure 13 are similar to those shown in connection with Figures 1 to 12 inclusive, except that the frame 287 is substituted for the twin-legged frame of Figures 1 to 12 inclusive. The operation has already been described in connection with the construction of the modification of Figures 13 to 15 inclusive, and requires no elaboration.

What I claim is:

1. An attachment machine adapted to be

mounted upon an upright frame portion of a jigsaw having a power takeoff shaft thereon, said machine comprising an attachment frame having an upright portion removably secured to said jigsaw upright portion, an attachment shaft journaled in said attachment frame, a rotary tool on said attachment frame drivingly connected to said attachment shaft, a power transmitting mechanism drivingly interconnecting said shafts, a clamping device releasably securing said attachment frame to said jigsaw frame and adjustment mechanism mounted on one of said frame portions and adjustably engageable with the other frame portion for moving said frame portions relatively to one another.

2. An attachment machine adapted to be mounted upon an upright frame portion of a jigsaw having a power takeoff shaft thereon, said machine comprising an attachment frame having an upright portion removably secured to said jigsaw upright portion, an attachment shaft journaled in said attachment frame, a rotary tool on said attachment frame drivingly connected to said attachment shaft, a power transmitting mechanism drivingly interconnecting said shafts, a clamping device releasably securing said attachment frame to said jigsaw frame and a rotary adjoining element mounted on one of said upright frame portions and adjustably engageable with the other upright frame portion for moving said frame portions relatively to one another.

3. An attachment machine adapted to be mounted upon an upright frame portion of a jigsaw having a power takeoff shaft thereon, said machine comprising an attachment frame having an upright portion removably secured to said jigsaw upright portion, an attachment shaft journaled in said attachment frame, a rotary tool on said attachment frame drivingly connected to said attachment shaft, a power transmitting mechanism drivingly interconnecting said shafts, a clamping device releasably securing said attachment frame to said jigsaw frame and rotary cam adjustment mechanism mounted on one of said frame portions and adjustably engageable with the other frame portion for moving said frame portions relatively to one another.

4. An attachment machine adapted to be mounted upon a pair of spaced upright frame portions of a jigsaw having a power take-off shaft thereon, said machine comprising an attachment frame having a pair of spaced upright portions removably secured to said jigsaw upright portions, an attachment shaft journaled in said attachment frame, a rotary tool on said attachment frame drivingly connected to said attachment shaft, power transmitting mechanism drivingly interconnecting said shaft, a clamping device releasably securing said attachment frame upright portions to said jigsaw frame upright portions and adjustment mechanism mounted on one of said frame portions and adjustably engageable with the other frame portion for moving said frame portions relatively to one another.

5. An attachment machine adapted to be mounted upon a pair of spaced upright frame portions of a jigsaw having a power take-off shaft thereon, said machine comprising an attachment frame having a pair of spaced upright portions removably secured to said jigsaw upright portions, an attachment shaft journaled in said attachment frame, a rotary tool on said attachment frame drivingly connected to said attachment shaft, power transmitting mechanism drivingly interconnecting said shaft, a clamping de-

vice releasably securing said attachment frame upright portions to said jigsaw frame upright portions and a rotary adjusting element mounted on one of said upright frame portions and adjustably engageable with the other upright frame portion for moving said frame portions relatively to one another.

6. An attachment machine adapted to be mounted upon a pair of spaced upright frame portions of a jigsaw having a power take-off shaft thereon, said machine comprising an attachment frame having a pair of spaced upright portions removably secured to said jigsaw upright portions, an attachment shaft journaled in said attachment frame, a rotary tool on said attachment frame drivingly connected to said attachment shaft, power transmitting mechanism drivingly interconnecting said shaft, a clamping device releasably securing said attachment frame upright portions to said jigsaw frame upright portions, a rotary adjustment shaft mounted on one of said frame portions, and a

pair of spaced cams mounted on said adjustment shaft and engageable with the other frame portion.

FREDERICK J. TOLLAFIELD.
